C. E. REDDIG

IRONING SHOE

Filed June 30, 1924

Inventor:
Charles E. Reddig.
by Edward A. Atty

UNITED STATES PATENT OFFICE.

CHARLES E. REDDIG, OF KEW GARDEN, NEW YORK, ASSIGNOR TO WESTERN ELECTRIC COMPANY, INCORPORATED, OF NEW YORK, N. Y., A CORPORATION OF NEW YORK.

IRONING SHOE.

Application filed June 30, 1924. Serial No. 723,139.

To all whom it may concern:

Be it known that I, CHARLES E. REDDIG, a citizen of the United States of America, residing at Kew Garden, Richmond Hill,

5 Long Island, in the county of Queens and State of New York, have invented certain new and useful Improvements in Ironing Shoes, of which the following is a full, clear, concise, and exact description.

10 This invention relates to shoes for power driven ironing machines. More specifically, it refers to an electrically heated ironing shoe which is particularly well adapted for use in an ironing machine of the type disclosed in Patent 1,526,374 granted to me February 17, 1925, which discloses an ironing machine in which a plurality of gas heated shoes are adapted to cooperate with their respectively associated ironing rolls for 15 ironing articles of different characters.

The object of this invention is to improve the construction of such ironing shoes.

In accordance with this invention the ironing shoe which coacts with the power roll comprises a metallic member carrying a heating unit, a switch being mounted on the shoe which contains terminals of the wires of the heating elements to control the current for heating the unit.

25 More specifically the shoe comprises a plano-concave metallic member, preferably a casting, supporting on its plane face the electric heating unit and its opposite concave face being adapted to cooperate with 30 the power roll, this shape providing for heating the effective portion of the shoe uniformly and economically at the required temperature.

Other features of this invention and advantages will appear from the following description and by the claims appended thereto, reference being had to the accompanying drawings in which:

Fig. 1 is an assembly view of the ironing shoe with portions of the heating unit and housing cut away.

Fig. 2 is a sectional view of the shoe taken approximately on line 2—2 of Fig. 1 and looking in the direction indicated by the arrows; and

Fig. 3 is a view similar to that of Fig. 2

showing an alternative arrangement of the heating elements in the shoe.

Similar reference characters refer to similar parts throughout this description.

The ironing shoe of this invention preferably consists of a plano-concave shaped casting 10, the concave side of which is adapted to cooperate with a power driven roll 12 which is generally covered with a pad 13 as shown in Fig. 2. On the plane surface 14 of the casting 10 is mounted a unit made up of a series of electrical heating elements which preferably consist of two parallelly disposed insulating strips 16 and 17 on which the metallic ribbons 15 and 18 are wound as shown in Fig. 1. The strips 16 and 17 are held in spaced relation by means of insulating strips 22 and 23 and the whole held in a metallic frame or envelope 24. This frame 24 is held securely against the plane surface 14 of the casting 10 by means of a metal plate 25 which is screwed to the casting by means of a number of screws 26, 27, etc., thus permitting the removal of the heating unit 25 for inspection or repairs.

An arcuated flange 29 inwardly lined with a strip of insulating material 30 is secured along the edge of the casting 10 and cooperates therewith to form a housing adapted to be filled with asbestos cement or any other like insulating material in order to confine the heat to the effective portion of the shoe.

The ends of the conducting ribbon or coil 15 are connected to the ends of wires 33 and 34 by means of screws 20 and 21 and the ends of the coil 18 are connected to the terminal of wires 35 and 36, by means of screws 20¹ and 21¹, respectively. The opposite ends of wires 33, 34, 35 and 36 are each connected to a switching device 37 which is disposed in a convenient place with reference to the operator of the machine. This switching device is mounted in a housing 38 preferably made integral with the arcuated flange 29 and is provided for controlling the heating elements 15 and 18 through the provision of a suitable multiple switching mechanism not shown. An insulating bushing 39 securely arranged in the housing 38 is provided for protecting and for holding the cord 40 in position.

The lugs 44 shown in Fig. 1 are preferably made integral with the casting 10 and are provided for pivoting the shoe on the machine in the manner described in the co-pending application above referred to.

In the modification shown in Fig. 3 the heating element is held securely in the convex side of the casting 10 by means of a plurality of arcuated clamps 42.

10 From the foregoing it will be seen that the present invention provides an improved shoe which has the advantages of—

1. Eliminating all exposed wires except the conductor cord.
- 15 2. It makes the shoe a complete unit.
3. It does not interfere in any way with the tipping back of the shoe for cleaning or waxing.
4. It is conveniently interchangeable with 20 gas-heated shoes now used in power ironing machine, requiring only the removal of the swivel pin in the toggle mechanism.
5. It permits the heat control of the shoe in accordance with heat requirement of the 25 articles to be ironed.

What is claimed is:

1. In combination, an ironing shoe com-

prising a metallic member, an electric heating element mounted on said member, a controlling switch mounted on said shoe, and a 30 conducting cord connected to said switch.

2. A ironing shoe comprising a plano-concave shaped metallic member, and a heating element mounted on the plane surface of 35 said member.

3. In combination, an ironing shoe comprising a metallic member, independent electric heating elements mounted on said member, and a manual switch mounted on said shoe for independently rendering effective 40 the heating elements.

4. An ironing shoe for a power driven ironing machine comprising a plano-concave shaped casting, an arcuated flange secured on said casting and arranged to form a 45 housing adapted to be filled with insulating material, a heating unit consisting of a plurality of independent coils in said housing, and a switching device mounted on said flange to render said coils effective with respect to said casting singly or collectively.

In witness whereof, I hereunto subscribe my name this 25th day of June A. D., 1924.

CHARLES E. REDDIG.
